UNITED STATES PATENT OFFICE.

EDWARD S. GILLESPIE, OF DETROIT, MICHIGAN.

ART OF COLORING MOVING-PICTURE FILMS.

1,342,803.

Specification of Letters Patent.

Patented June 8, 1920.

Application filed February 9, 1918. Serial No. 216,410.

To all whom it may concern:

Be it known that I, EDWARD S. GILLESPIE, a citizen of the United States, residing at Detroit, in the county of Wayne and State 5 of Michigan, have invented new and useful Improvements in the Art of Coloring Moving-Picture Films, of which the following is a specification.

This invention relates to the art of coloring moving picture films.

An object of the invention is to produce printing rollers of simple and improved construction whereby coloring matter may be applied to the film.

15 Further objects of the invention are to simplify and improve the construction and arrangement of parts comprising the invention.

With these and other ends in view which 20 will readily appear as the nature of the invention is better understood, the same consists in the improved construction and novel arrangement and combination of parts which will be hereinafter fully described and particularly pointed out in the 25 claims.

In the accompanying drawings has been 30 illustrated a simple and preferred form of the invention, it being, however, understood that no limitation is necessarily made to the precise structural details therein exhibited, but that changes, alterations and modifications within the scope of the claims may be resorted to when desired.

35 In the drawings:

Figures 1, 2 and 3 are plan views of different forms of printing rollers, in connection with my invention.

40 Figs. 4, 5 and 6 are end views of the rollers shown in Figs. 1, 2 and 3, respectively.

Fig. 7 is a diagrammatic view showing a pair of the rollers illustrated in Fig. 1 arranged in position for operation and 45 showing also pressure rollers co-acting therewith and a strip of film passing between the printing rollers and the pressure rollers.

Fig. 8 is an edge view of the parts shown 50 in Fig. 7.

Fig. 9 is a plan view of a portion of a moving picture film showing a moving object in progressively advanced position and illustrating how a portion of the emulsion

is removed from the face of the film in carrying out a part of the improved process.

Fig. 10 is a plan view of one of the printing pads with its foundation complete.

Fig. 11 is a sectional view taken on the line 18—18 in Fig. 10.

Corresponding parts in the several figures are denoted by like characters of reference.

A printing roller illustrative of the most simple form of my invention is shown in 65 Figs. 1 and 4. The roller which may be constructed of any suitable metal such as brass or aluminum may be of any desired diameter although it is desirable to adopt a standard diameter for this as well as for 70 other forms or types of rollers to be herein-after described. In order that such rollers may be interchangeably mounted in a machine frame of standardized construction, the roller seen in Figs. 1 and 4 is to 75 be of a width corresponding with the width of a standard picture film. The roller which is designated by numeral 15 is provided with grooves or channels 16 extending transversely across the face thereof in parallel relation to the axis of the roller each of said grooves being of a width equal to the height of an individual film picture, each of the arcuate raised portions separated by said grooves being also of a width equal to 85 the height of a standard film picture, said raised portions constituting what I shall call the printing faces 17. The printing faces 17 are provided with spurs 18 adjacent to the ends thereof, said spurs being 90 for engagement with the perforations 19 in the strip of film a portion of which is seen at 20 in Figs. 7 and 8.

In preparing the printing roller for actual use, the printing faces of said roller are to 95 be provided with printing pads some of which may be seen at 21. These pads must, of course, be properly positioned and each pad must be of an area corresponding with the area of the film picture to be colored. 100 Thus, if the entire surface of the film picture is to receive one solid color, the area of the printing pad must correspond with the area of the film picture. If, on the other hand, only a portion of the picture is to be 105 colored, the area and location of the pads must correspond to such portion. To illustrate: if the picture is to show a green lawn

and a blue sky, printing pads will first be arranged to apply the one color to the proper portion of each film picture, the other color being applied by rollers having differently arranged pads and at a subsequent operation.

The printing pads used in connection with the invention are preferably of composite structure, each pad consisting of a base *a* and a facing *b*. The base is preferably made of a piece of celluloid such as is employed in the manufacture of films, said celluloid having the customary perforations at the sides thereof which will be adapted to engage the teeth of the rollers adjacent to the printing faces. The facing *b* consists of a thin coating of gelatin or other suitable material which will absorb and transfer the ink or coloring solution that is being used and which will be rejected by celluloid. In the preferred method of carrying out the invention a printing pad consisting of a gelatin coated piece of celluloid is cemented on each printing face of a roller. I then take a reproduction of the film which is to be colored and remove from the face of each picture of such reproduction a portion which corresponds with the moving object that is to be colored. Thus, in Fig. 9 I have shown a portion of a film, some of the pictures of which represent a ball in progressively advancing position. That portion of the emulsion which represents the ball is removed from each picture. The film is then soaked in coloring solution which is absorbed by the emulsion but is rejected by that portion of the celluloid base which has been exposed by removing the emulsion. The printing roller having the printing pads applied thereto is now placed in the machine mounted in such a manner as to permit the prepared film to be run over the same, leaving an impression on the face of each printing pad. The portion of the facing on each pad which has thus been colored is now removed, leaving in position just that portion which is necessary to apply coloring matter to the film that is to be colored. It follows that when the film that is to be colored receives an impression from the roller, just those portions of the film pictures which are to be colored will receive impressions, assuming, of course, that the film and the printing roller have been placed in proper registry before the beginning of the operation.

It is evident that a roller construction, as seen in Figs. 1 and 4, will apply coloring matter only to every alternate picture of a film owing to the presence of the grooves or channels 16 in the interspaces between the printing faces. The particular reason for forming these grooves or channels is to avoid any possibility of coloring substance being permitted to overlap the pictures thereby producing blotches and a general unsightly appearance. In order to avoid the necessity

of passing the film twice through a machine when this form of roller is used, it is the intention to use two rollers simultaneously, as clearly seen in Figs. 7 and 8, where the rollers have been shown diagrammatically 70 as well as the pressure rollers 23 and the strip of film 20. The rollers 15 are supported for rotation in spaced relation, the pressure rollers being also mounted for rotation in such a fashion that they will contact with the printing pads of the respective printing rollers, the pressure rollers being of such width that they will engage between the spurs 18 adjacent to the ends of the printing roller. The rollers are so arranged 75 that while one roller will apply coloring substance to alternate pictures the intermediate pictures will receive coloring substance from the other roller. Thus, at a single operation, coloring substance may be applied to each 80 picture of a film irrespective of the length of the latter.

The invention as thus far described is applicable to the coloring of film pictures where objects to be colored are stationary 90 or where a single color is applied to the entire area of the picture. Where moving objects are shown in a film a printing roller of a somewhat different construction is employed, specimens of such rollers having 95 been shown in Figs. 2, 5, 3 and 6 of the drawings. In these rollers the printing faces, here designated by 35, are disposed spirally with respect to the circumference of the roller, and the latter is made of a 100 length to contain any number of spirals that may be found necessary to color that portion of the film in which the moving object appears. The printing pads, here designated by 36, the outlines of the gelatin faces of 105 which obviously must correspond with the outlines shown in the film pictures, are arranged in progressive order around the circumference of the roller, the position of the pad on each printing face being advanced 110 to correspond with the position of the image in the picture. Thus, assuming that the moving object is shown in a consecutive series of fifty pictures and that each spiral of the roller contains ten printing faces, it 115 is obvious that five such spirals would be required to apply color to the portion of the film having the picture showing the moving object. When such a roller is used, it must obviously be mounted for longitudinal sliding movement axially, the roller being advanced by engagement with the film, or the film must be mounted in such a manner as to be capable of traversing the face of the roller longitudinally. The roller, of course, 120 may be of any length to provide the requisite number of printing faces.

By the construction shown in Figs. 2 and 5 the face of the roller is provided with obliquely disposed grooves 38 corresponding 130

to the grooves 16 in Figs. 1 and 4. By the construction shown in Figs. 3 and 6 the roller is provided with printing faces disposed contiguously and merely separated by 5 narrow V-shaped grooves 40 of sufficient depth to receive any possible overflow of coloring solution without danger of blotching or marring the pictures.

From the foregoing description taken in 10 connection with the drawings hereto annexed, it will be seen that I have provided a simple, effective and inexpensive method and device for coloring moving picture films whether moving objects or stationary objects 15 only are to be colored.

Having described the invention what I claim as new is:

1. A printing roller for coloring picture films, said roller having circumferentially 20 disposed printing faces and grooves separating said printing faces, and individual printing pads affixed on said faces.

2. A printing roller for coloring picture films, said roller having circumferentially 25 disposed printing faces and grooves separating said printing faces, and printing pads affixed on said faces, said pads being saturated with coloring solution.

3. A printing roller for coloring picture 30 films, said roller having circumferentially disposed printing faces and grooves separating said printing faces, spurs adjacent to the edges thereof and printing pads affixed on said spurs.

35 4. A printing roller for coloring picture films, said roller having circumferentially

disposed printing faces and grooves separating said printing faces, and printing pads secured on said faces, each pad composed of a base of non-absorbent material and a fac- 40 ing of absorbent material.

5. A printing roller for coloring picture films, said roller having circumferentially disposed printing faces and grooves separating said printing faces, spurs adjacent to the 45 edges thereof and printing pads affixed on said faces, said pads including each a base portion of non-absorbent material having perforations engaging the spurs, and a fac- 50 ing of absorbent material, the area of which is confined between the spurs.

6. A printing roller for coloring picture films, said roller having circumferentially disposed printing faces and grooves separating said printing faces, spurs adjacent to the 55 edges thereof and printing pads affixed on said faces, said pads including each a base portion of non-absorbent material having perforations engaging the spurs, and a fac- 60 ing of absorbent material, the area of which is confined between the spurs, said facing being of an area, outline and location corresponding with the impression to be made.

7. A printing roller for coloring picture films having spaced grooves in the periphery 65 thereof to provide alternate raised portions and depressions, the raised portions defining printing faces spaced apart around the periphery of the roller by the grooves.

In testimony whereof I affix my signature. 70

EDWARD S. GILLESPIE.
